Patented Nov. 2, 1971

222,546

ELECTRIC INDICATOR PANEL FOR A PNEUMATIC TUBE SYSTEM

Herbert Kalendar, Hallandale, Fla., assignor to Advance
Metal Products, Inc., Miami, Fla.

Filed Sept. 10, 1970, Ser. No. 24,909

Term of patent 14 years

Int. Cl. D13—03

U.S. Cl. D26—13

The figure is a perspective view of an electric indicator panel for a pneumatic tube system, showing my new design.

The rear side thereof is plain.
I claim:

The ornamental design for an electric indicator panel for a pneumatic tube system, as shown and described.
